UNITED STATES PATENT OFFICE.

GUSTAF JOHANSSON, OF BAY CITY, MICHIGAN.

DISPLAY RACK.

Application filed September 10, 1923. Serial No. 661,801.

This invention relates to display racks and the like.

One object of the invention is to design a novel and convenient display rack for displaying bolts of cloth and other goods which is manufactured in predetermined widths and of varying lengths.

Another object is to design a durable and compact rack upon which a large number of bolts or rolls of goods can be displayed.

A further object is to provide a stationary track and movable trolley comprising a plurality of hangers which can be pulled outwardly, and the individual racks swung as desired to allow all the goods to be simultaneously and attractively displayed.

A still further object is to provide a display rack which can be compactly folded so as to occupy but a minimum of floor space.

A further object still is to provide a display rack on which the bolts of cloth can be readily placed or removed, and from which any length of cloth may be cut from any bolt without removing it from the rack, and with ease and simplicity by the clerk.

With the above and other objects in view the present invention consists in the combination and arrangement of parts, herein after more fully described, illustrated in the accompanying drawings, and particularly pointed out in the appended claims, it being fully understood that changes may be made in the form, size, proportion and minor details of construction, without departing from the spirit or sacrificing any of the advantages of the invention.

In the drawings.

Fig. 1 is a side elevation of the display rack illustrating it in folded position.

Fig. 2 is an end view thereof, the center hanger being broken away to show the supporting column.

Fig. 3 is a fragmentary end view of one of the hangers illustrating the manner of removing cloth from one of the lower bolts or rolls.

Fig. 4 is a top plan view of the display rack shown in two different positions, the full lines illustrating it folded, and the dotted line showing it extended and the hangers swung for display purposes.

Fig. 5 is a sectional view of the lower stabilizer or support.

Fig. 6 is a similar transverse sectional view.

Fig. 7 is a top plan view thereof, and also illustrating the bottom guide rail.

Heretofore it has been general practise in merchandising establishments, to place bolts of cloth in rows on built up flat shelving, this leaves only the end of the bolt exposed, consequently it must be taken from the shelf, placed on a counter and unrolled for display, if a number of pieces are shown they must necessarily be placed one on the other, this results in a disordered and untidy appearance and these rolls or bolts must each time be again rolled and placed on the shelf in order to clear the counter, as the next customer may desire something entirely different; this means continuous labor, disordered counters, and space sufficient for the shelves, clerks' aisle, counter and customers' aisle. In my improved display rack, space and labor is minimized, the goods are always in position for inspection by the customer who can choose and select without having the clerk in attendance taking down and displaying the goods, and the entire rack can be compactly folded, locked and rolled against the wall, leaving the entire floor space clear and free from counters, etc.

Referring now particularly to the accompanying drawings in which I have shown the preferred embodiment of my invention, the numeral 1 indicates a permanent trolley rail, one end of which is provided with a bracket 2 secured thereto, and this end is adapted to be permanently secured to the wall or a portion of the building, the free end is provided with a gusset plate which serves as a stop and to which a stay rod or cable 3 is attached, the opposite end of this cable being anchored to the wall or ceiling as required.

A trolley 4 is mounted for travel on this rail 1, and is provided with the spaced apart rollers 5 which engage the top of the rail, a similar roller 6 being journaled on the trolley as shown, and engages the bottom web of the rail to prevent the tipping or binding of the structure.

A plurality of hanger arms 7 are pivotally mounted between the flanged portions 8 of the trolley 4 by means of the pins 9, these portions being reinforced by means of the webs 8^a. A vertically disposed pipe member 10, provided with flanges 10^a, is adapted to be secured to the member 8 by means of bolts or the like, the lower threaded end engaging an internally threaded casting 11,

formed as clearly shown in Figs. 5 and 7. Horizontally disposed rollers 12 are journaled in this casting 11 in spaced relation and are adapted to engage a guide rail 13 which is secured to the floor of the building. This rail serves as a guide and the small rollers readily roll thereon and stabilize the structure.

Hanger bars 14 are secured between the lugs 7^a which are cast integral with the hanger arms by means of bolts or the like, and these bars are formed with spaced apart inclined slotted openings 15 adapted to receive a bar 16 which serves as a core on which the cloth 17 is rolled, and while in the present instance I have shown but three hangers, designed to hold eight rolls of cloth each, it will be readily understood that any desired number of hangers may be used, and these can be designed to receive any reasonable number of rolls of material.

The rolls of cloth on the lower end of the rack will of course be close to the floor, and to eliminate the stooping, etc., when removing a length of cloth from one of these lower rolls, I have provided a small roller 18 which is journaled in a pair of hangers 19 pivotally secured to the lugs 7^a as shown, in the present instance I have shown a roller attachment for each pair of hanger bars, but this is not necessary, as but one need be provided, and can be detachably connected and only attached when it is desired to remove material from one of the lower rolls.

A receiving shelf 20 is also secured to and connects the lower ends of the hanger bars together, the sides being extended and bent at an angle to remove the material and when removing the material from one of the lower rolls, the clerk places the end of the cloth over the roller 18 the material dropping into the receiving shelf 20 as it is measured, all as clearly illustrated in Fig. 3 of the drawings. These shelves and small rollers 18 must necessarily be staggered to prevent binding when the rack is closed. A yard stick or tape (not shown) can also be attached to the frame 19 so that the material can be measured as it is unwound.

For convenience in pulling the rack out preparatory to opening it for display, I have provided a rod 21 which is anchored to the post 10, this extends through the center hanger arms, terminating in a swiveled handle 22 to which a locking bar 23 is secured. Clips 24 are secured to each of the outside hanger bars and these clips are adapted to receive the end of the bar 23 for holding the

rack in locked position as shown in full lines in Figs. 1 and 2, but when the bar is turned to position as indicated by dotted lines in Fig. 2 the hangers are free to swing on their pivots, as illustrated by the dotted lines in Fig. 4, and by pulling the rack out also as illustrated by the dotted lines in the same figure, and then swinging the arms as above described, customers can readily inspect both sides of each individual row of material.

From the foregoing description it will be obvious that I have perfected a simple, convenient, and economical display rack, which will neatly and tastily display a large number of rolls of material.

What I claim is:—

1. The combination with a fixed rail, of a trolley mounted thereon, horizontally extending hanger arms pivotally secured at their inner ends to said trolley, and spaced apart hanger bars depending from said hanger arms.

2. The combination with upper and lower fixed rails, of a trolley mounted on the upper rail, a post secured to said trolley and engaging the lower rail, horizontally extending hanger arms pivotally secured at their inner ends to said post, and spaced apart hanger bars depending from said arms.

3. The combination with a fixed rail, of a trolley mounted thereon, horizontally extending hanger arms pivotally secured at their inner ends to said trolley, spaced apart hanger bars depending from said arms and provided with slotted openings adapted to receive rolls of material between them, and a receiving shelf connecting the lower ends of said bars.

4. A display rack comprising a trolley a vertically disposed post secured thereto, hanger arms pivotally secured to the post in spaced apart relation, spaced apart hanger straps depending from said arms and provided with slotted openings adapted to receive rolls of material between them, means for locking said hangers in folded position, and a handle for manually operating said rack.

5. A display rack comprising a trolley having a vertically disposed post secured thereto hanger arms pivotally secured to the post, spaced apart hanger bars depending from said arms, and an auxiliary roller frame detachably journaled to said hanger arms.

In testimony whereof I affix my signature.

GUSTAF JOHANSSON.
